US00D752383S

(12) **United States Design Patent**
Zox

(10) **Patent No.:** **US D752,383 S**
(45) **Date of Patent:** **** Mar. 29, 2016**

(54) **PLATE GRIP**

(71) Applicant: **Holdaplate, LLC**, New York, NY (US)

(72) Inventor: **John Zox**, New York, NY (US)

(73) Assignee: **HOLDAPLATE, LLC**, New York, NY (US)

(**) Term: **14 Years**

(21) Appl. No.: **29/511,196**

(22) Filed: **Dec. 8, 2014**

Related U.S. Application Data

(63) Continuation of application No. 29/471,214, filed on Oct. 29, 2013, now Pat. No. Des. 720,179.

(57) **CLAIM**

The ornamental design for a plate grip, as shown and described.

DESCRIPTION

FIG. 1 is a top view of the plate grip of the present invention, showing the new design;

FIG. 2 is a bottom view of the plate grip of FIG. 1;

FIG. 3 is a first side view of the plate grip of FIG. 1;

FIG. 4 is a second side view of the plate grip of FIG. 1;

FIG. 5 is a back view of the plate grip of FIG. 1;

FIG. 6 is a cross section view of the plate grip at line 6-6 of FIG. 1;

FIG. 7 is a cross section view of the plate grip at line 7-7 of FIG. 1;

FIG. 8 is a bottom perspective view of the plate grip of FIG. 1;

FIG. 9 is a side perspective view of the plate grip of FIG. 1; and,

FIG. 10 is a bottom perspective view of the plate grip of FIG. 1.

The evenly spaced broken lines depict portions of the plate grip that form no part of the claimed design.

1 Claim, 8 Drawing Sheets
